UNITED STATES PATENT OFFICE.

HUGO F. SCHROEDER, OF TORRINGTON, CONNECTICUT, ASSIGNOR TO SCHROEDER BROTHERS MANUFACTURING COMPANY, OF TORRINGTON, CONNECTICUT, A COPARTNERSHIP.

SEAMING-MACHINE.

1,325,210.

Specification of Letters Patent.

Patented Dec. 16, 1919.

Application filed September 3, 1918. Serial No. 252,306.

To all whom it may concern:

Be it known that I, HUGO F. SCHROEDER, a citizen of the United States, residing at Torrington, in the county of Litchfield and 5 State of Connecticut, have invented certain new and useful Improvements in Seaming Machines, of which the following is a specification.

This invention relates to seaming machines. The stock upon which the machine operates and the use to which the article which is seamed by the machine is to be put may vary decidedly. The machine has been found quite satisfactory in the sheet metal 15 art; and specifically for employment in the production of a radiator and particularly the body thereof. In some radiators such as are found in automobiles, the body as it is known, is of sheet metal. By the machine 20 the ends of the body are brought together and seamed substantially together, and while the seaming action is occurring the trimming of the stock along its edge is taking place, so that the product presents a 25 finished appearance. I provide a machine which is simple in construction, quite compact, efficient in action and by which the desired results can be obtained in a rapid manner.

30 In the drawings accompanying and forming part of the present specification I show in detail one advantageous form of embodiment of the invention which I will set forth fully in the following description, so that 35 those skilled in the art can practice the invention. I do not necessarily restrict myself to this particular showing; I may depart therefrom in several ways within the scope of the invention defined by the claims 40 following said description.

Referring to said drawings:

Figure 1 is a top plan,

Fig. 2 a side elevation as seen from below in Fig. 1, and

45 Fig. 3 a front view as seen for instance from the left in Figs. 1 and 2, of a seaming machine involving the invention the head and parts carried thereby being omitted.

Fig. 4 is an outside view of the seaming 50 and trimming or cutting head.

Fig. 5 is a bottom plan view of the same, and

Fig. 5^a a view as seen from the right in Fig. 4.

Figs. 6 to 10 inclusive are cross sections on 55 the lines 6—6 to 10—10 respectively of Fig. 4, the arrows applied to the respective section indicating lines, denoting the points of view.

Like characters refer to like parts 60 throughout the several views, Figs. 6 to 10 being on larger scales than the other views, and Figs. 4 to 5^a inclusive being on larger scales than Figs. 1, 2 and 3.

The different parts of the machine may be 65 sustained in any desirable way. The framing shown for this purpose includes a base or bed 2 and a block as 3 rising from the base or bed, the two parts being usually in one piece. The base or bed may have at 70 suitable places perforations or holes as 4 to receive screws, bolts or equivalent means by which said base or bed can be fastened to a suitable foundation. There is suitable 75 work or stock holding means and suitable 80 means for seaming and cutting, and although these may be related in various ways, I prefer that the work be fixed and that the seamer and cutter move, the seaming and 85 cutting operations occurring during such movement. As a matter of fact in the present case the cutting occurs first or is continued during the seaming action, the result being that when the article has received the necessary actions, it has a neat finish. 85

On one side of the base or bed 2 and located in proximity to the block 3 which directly supports the seaming and cutting mechanism, is a bracket as 5 of elbow or L-form, the flange of the bracket being fastened as by screws 6 to the upper side of the base or bed. This bracket has its front face or edge in transverse line with the corresponding portion of the block 3, the inner flat face of the bracket being spaced from 90 the block, the interval or space between the two parts being designated by 7. The work holder which directly supports the work during the seaming and cutting operations is sustained upon the inner side of the 100 bracket 5, the body thereof having the way 9 in which the work holder is set in such fashion that the outer face of the work holder extends a short distance beyond the corresponding surface of the body of the 105 bracket 5. This work holder comprises the superposed elements 10, 11 and 12 which are initially spaced apart as shown in both

Figs. 2 and 3 to receive between them the two portions of the stock or work 13. The leaves or portions of the stock or work are inserted in the spaces between the respective elements 10, 11 and 12, after which they are operated by the cam 14 to cause said elements to clamp the work in such way that the two parts thereof extend beyond the work holder enough to be acted upon by the cutting and seaming means. The cam 14 as shown is pivoted as at 15 on the bracket 5 and has a manipulating portion or handle 16 by which the elements 10, 11 and 12 can be operated to substantially clamp the work 13 with the ends of the work projecting inwardly or toward the right in Fig. 3 from the work holder 8. The projecting portions of the work as will be understood are those which are seamed or cut or trimmed by the appropriate moving means.

The seaming and cutting means includes a reciprocating head as 17 hereinafter more particularly described. This head 17 (Figs. 4 to 10 inclusive and best in Figs. 4 to 5^a) as will be understood, is reciprocating. As shown it is set in a notch 18 in the carrier 19 which is in the form of a slide. The carrier or slide 19 is provided with screws 20 engaging the upper and lower sides of the head 17 so as to rigidly hold the head of the carrier. As represented the carrier or slide 19 is of dove-tail form in cross section to fit a correspondingly shaped groove or channel 21 in the block 3, the groove or channel obviously being open at its ends to permit of the necessary stroke of the head 17. As shown there is rigidly connected with said head the rack bar 22 coextensive with the carrier or slide 19 to which the same is suitably rigidly connected as by screws 23. In mesh with the teeth of the rack bar is a pinion 24 fast on the shaft 25 supported about the center of the block 3 in suitable bearings carried thereby. The pinion is united with the inner end of the shaft. The latter at its outer end has rigidly connected therewith the hand wheel 26, through the primary agency of which, together with the associated described parts the head 17 may be given the necessary movement which in the present case is a reciprocation. I have described a way of operating this head 17 or its equivalent. The action in the present case is a manual one. It is clear, of course, that it can be accomplished by power, and it is equally apparent that the head, as I have considered it, need not be given a reciprocation, although this particular motion is a desirable one.

The head 17 comprises a body portion as 27 having on its outer side the rabbet 28 which extends from the front of the body portion almost to the back thereof. The rabbet in turn has at its forward end a rabbet 29. In this rabbet 29 is closely fitted the

projection or tongue 30 of the member 31 held to the body in some suitable way as by the screw 32, the head of which like other screws is countersunk in the back of the body portion 27. The front face of this 70 seaming member 31, it functioning in this particular, is flush with the front end of the body portion 27. The auxiliary rabbet 29 obviously is at one front corner of the main rabbet 28. At the opposite corner of said 75 main rabbet 28 is a seaming member 33 held in the rabbet as by the screw 34. The seaming member 33 is longer than the seaming member 31. In line longitudinally of the head 17 with the seaming member 31 is a 80 seaming member 35 which abuts against the seaming member 31 at its front end and is held in place to the body portion 27 by the screw 36. The seaming member 33 on the opposite side of the head overlies the seaming member 35 for practically half its length. The seaming member 35 is abutted by the seaming member 37 held in place by the screw 38, and the latter in turn is abutted by the seaming member or block 39 held in 85 place by the screws 40, the seaming member 39 abutting against the shoulder or stop presented by the rear wall of the main rabbet 28. The length of the seaming member or block 39 is equal as shown to the width of 90 the body portion 27. The seaming members or blocks 31, 35 and 37 are on one side of the head 17 longitudinally thereof. On the other side of the head is the seaming member 33 and others now to be described. The 95 seaming member 33 is abutted by the seaming member 41 held in place by the screw 42 and abutted in turn by the seaming member 43, held in place by the screw 44. Fastened to the front end of the body portion 27 is 100 the angular member 47, screws as 48 passing through the body or base of this angular member, which body or base fits flatwise against the body portion 27 and similarly against the seaming members 31 and 33. 105 The web of this angular member has an open slot 49, the side walls of which diverge outwardly, the slot extending back to the front end of the body portion 27. The seaming and cutting head 17 has on the inner surface 110 thereof the channel or groove 50 which extends centrally of the several seaming members and also of the back end of the inner side of the body portion 27 with which it will be remembered several seaming members are removably connected. This channel has its longitudinal axis coincident with that of the open-ended slot 49, the channel, however, being as shown a little wider than the slot. The width of the channel in fact defines the width practically of the seamed portion of the stock, said seamed portion relatively traversing said slot during the seaming and cutting operations.

Practically the initial operation which en- 115

sues is the cutting operation, and to secure this particular function a cutter or knife as 51 may be utilized. This cutter or knife is virtually triangular and is fastened as by 5 the screw 52 to the under side of the overhanging portion of the angular member 47, the cutting edge of the said cutter or knife 51 extending obliquely across the slot 49, so that as the stock traverses said slot, it 10 will be cut or trimmed. Said cutter or knife it will be understood, fits flatwise against the inner surface of the overhanging portion of the angular member 47, the back or inner edge of the knife or cutter fitting 15 solidly against the body of the angular member as clearly shown in both Figs. 4 and 5.

At the front upper side of the body portion 27 is a bead 53 which in the present 20 case is integral with said body portion. This bead extends into the slot 49 for practically half of its length, the rear part thereof being of course, rigid with the said body portion 27. The front part of this bead or 25 spacing member is separated from the walls of the slot 49 a distance agreeing practically with the width of the stock being operated upon. It will be understood that the stock relatively passes through the spaces between 30 the bead or spacing member 53 and the walls of the slot. The lower surface of this bead or rather the projecting portion thereof is in the plane of the bottom surface of the overhanging portion of the angular member 35 47. The front end of the bead or spacing member 53 is somewhat pointed or acute to properly enter the two sides or lateral portions of the stock to be seamed and cut. This pointed forward portion is of course, a 40 short distance in advance of the cutting edge of the knife or cutter 51.

As already indicated the stock or work is clamped in the work holder 8 with the edge portions of the two sides or lateral 45 parts of the work projecting inwardly from the work holder which is obviously toward the right in Fig. 1. On the advance of the 50 seaming and cutting head 17 in the manner set forth, the two sides of the work will enter the slot 49 and as said head 17 continues its advance, (toward the left in Figs. 1 and 2), the sides of the work will pass along said slot and through the passages at 55 opposite sides of the bead 53. Fig. 6 shows the sides of the work just after the slot 49 has been entered, and when said sides are in straddling relation with the forward projecting end of the bead 53, the relatively fixed cutter or knife 51 will trim off the 60 outer ends of said two sides. The cutting operation as will be inferred is a continuous one. After the initial action of the cutter on the work, the latter is laterally bent as will later appear and certain other operations 65 occur in proper sequence so as to secure

not only a close seam but one that is actually water-tight and quite finished.

As the head continues to advance and after the sides of the work have been subjected to the trimming in the manner indicated, 70 one side of the work will enter the channel or space 54 between the rear end portion of the bead 53 and the adjacent seaming member or block 31, and the other side of the work will enter the space between the said 75 bead and seaming member or block 33 so as to give each of the sides an L-bend or angular flange as 55 and 56 respectively as shown in Fig. 7. It will be seen upon an inspection of said Fig. 7 for instance, that the 80 vertically disposed body of the flange 55 is narrower than the corresponding part of the complementary L-flange; while the horizontal portion of the flange 55 is wider than the horizontal portion of the flange 56, these 85 flanges being shaped up obviously through the action of the camming surfaces of the seaming members 31 and 33. The rear portion of the block 33 has a cam surface 57 which bends the longer portion of the flange 90 55 vertically upon the outer edge of the horizontal portion of the flange 56 as shown in Fig. 8. Continuing, the free portion of the flange 55 is bent around the flange 56 as shown in Fig. 9. On the final movement 95 of the part 17 the two locked-together portions are pressed against the vertical bodies of the flanges as shown in Fig. 10.

There are two rows of blocks as will be understood. One of these rows comprises 100 the blocks 31, 35 and 37, while the other row comprises the blocks 33, 41 and 43. The end portions of certain of the blocks of the rows are transversely out of line with each other. For instance, the rear end portion of the block 41 is out of line with the rear end portion of the block 35 and out of line also with the front end portion of the block 37. The front end portion of the block 43 is 105 out of transverse line with the front end portion of the block 37.

What I claim is:

1. A machine of the class described comprising a supporting member, a plurality of blocks mounted thereon in rows with the co-operating faces of the blocks spaced apart, a block coextensive with the end blocks of each row at one end of the supporting member, some of the opposed blocks in different rows being of relatively different lengths, means 115 for supporting pieces of stock and for entering the edge portions of the stock into the space between the two rows of blocks, and means for causing a relative motion between the two rows of blocks and the stock-supporting means to thus cause said edge portions to traverse the space between the blocks, the blocks being furnished with means to seam together said edge portions and subsequently flatten down the seamed 120 130

portion of the stock on relative motion of the blocks and the stock-supporting means.

2. A machine of the class described comprising a supporting member, a block extending transversely thereof and having a groove at one edge, a series of blocks arranged at opposite sides of the supporting member with adjacent coöperating work engaging faces spaced apart and alined with the groove in the aforesaid block, means for supporting pieces of stock and for entering the edge portions of the stock into the space between the rows of blocks, means for causing relative motion between the two rows of blocks and the stock-supporting means to thus cause said edge portions to traverse the space between the blocks, the blocks being furnished with means to seam together said edge portions and subsequently flatten down the seamed portion of the stock on relative motion of the blocks and the stock-supporting means, and means for trimming off a part of the stock before the pieces thereof enter the space between the rows of blocks.

3. A machine of the class described comprising a supporting member, a block extending transversely thereof and having a groove at one edge, a series of blocks arranged at opposite sides of the supporting member with adjacent coöperating work engaging faces spaced apart and alined with the groove in the aforesaid block, the blocks being relatively immovable, means for supporting pieces of stock and for entering the edge portions of the stock into the space between the rows of blocks, means for causing relative motion between the two rows of blocks and the stock-supporting means to thus cause said edge portions to traverse the space between the blocks, the blocks being furnished with means to seam together said edge portions and subsequently flatten down the seamed portion of the stock on relative motion of the blocks and the stock-supporting means, and means for trimming off a part of the stock before the pieces thereof enter the space between the rows of blocks.

4. A machine of the class described comprising a supporting member, a block extending transversely thereof adjacent one end, a row of juxtaposed blocks immovably mounted at each edge contacting the transverse block, the work engaging faces of the rows of blocks being spaced apart, means for supporting pieces of stock and for entering the edge portions of the stock into the space between the rows of blocks, a single block at the rear end of the two series and extending across the space between said series, and means for causing a relative motion between the blocks and the stock-supporting means to thus cause said edge portions to traverse the space between the blocks and the blocks being furnished with means to seam together said edge portions and the single block being equipped with means to flatten down the seamed portion of the stock on relative motion between the blocks and the stock-supporting means.

5. A machine of the class described comprising a supporting member, a series of blocks of different cross sectional areas arranged in juxtaposition adjacent each edge of the supporting member and being relatively immovable, elements between which portions of the stock are supported and clamped, while the edge portions of the stock are entered into the space between the two rows of blocks, and means for causing a relative motion between the two rows of blocks and said elements to cause the edge portions of the pieces of stock to traverse the space between the blocks, the blocks being furnished with means to seam together said edge portions and subsequently flatten down the seamed portion of the stock on relative motion of the blocks and the stock supporting means.

In testimony whereof I affix my signature in the presence of two witnesses.

HUGO F. SCHROEDER.
